FOREIGN PATENT DOCUMENTSPCT/US94/
01496 2/1994 WIPO.*Primary Examiner*—Ruth McInroy
Attorney, Agent, or Firm—Varnum, Riddering, Schmidt & Howlett LLP[57] **CLAIM**

The ornamental design for combined hose and storage rack, as shown and described.

DESCRIPTION

FIG. 1 is a perspective view of a combined hose and storage rack showing our new design;

FIG. 2 is a front-elevational view thereof;

FIG. 3 is a right, side-elevational view thereof;

FIG. 4 is a rear-elevational view thereof;

FIG. 5 is a left side-elevational view thereof;

FIG. 6 is a top plan view thereof; and,

FIG. 7 is a bottom plan view thereof.

The broken line showing of the cleaner housing and cleaning tool in FIGS. 1-7 is for illustrative purposes only and forms no part of the claimed design.
